DRAIN OUTLET AND THE METHOD OF MAKING SAME

Patrick F. Donahue, Waterbury, Conn., assignor
to Scovill Manufacturing Company, Waterbury,
Conn., a corporation of Connecticut

Application December 6, 1945, Serial No. 633,102

8 Claims. (Cl. 4—288)

1

This invention relates to plumbing fixtures and particularly to a drain fitting such as used in connection with sinks or lavatory bowls.

One object of this invention is to improve the strainer member that is usually incorporated into such drain fittings.

Another object is to position the strainer member of this fitting in such a manner that it will not obstruct the overflow drainage outlets.

It has been customary in such drain fittings to provide fingers integrally formed out of the stock of the fitting and disposed in an inwardly radial manner to act as the strainer for the drain fittings and prevent large objects, such as soap pieces and the like, passing into the drainage pipes. These fingers initially are disposed across the drainage openings in the side walls of the fitting and in the past it has been customary to form such fingers radially inward from the lower edges of said openings. It is the purpose of my invention to improve the construction by forming the fingers inward from the upper edge of the drain openings so as not to interfere in any way with the overflow drainage system.

Another object is to interconnect the free ends of the fingers in such a manner that they will be rigidly interconnected together and cannot be readily pried apart as individual members, this being accomplished by an axial swaging operation that drifts the metal disposed in the ends of the fingers into an interconnected mass at the center of the drain fitting.

Other objects and advantages of the invention will be apparent from the following description taken in connection with the drawing in which—

Fig. 1 is a vertical sectional view through a drain fitting shown as assembled into a fragmentary portion of a lavatory bowl.

Fig. 2 is a side elevational view of the drain fitting, per se.

Fig. 3 is an upper plan view of the same and showing the strainer fingers in their completed state.

Fig. 4 is a view similar to Fig. 3 but showing the inner ends of the strainer fingers as they appear before the swaging operation.

Fig. 5 is an enlarged fragmentary sectional view through the body portion of the drain fitting taken substantially along the line 5—5 of Fig. 3.

Fig. 6 is a fragmentary plan view of the inner ends of the strainer fingers to show particularly the results of this swaging operation and the manner in which the apical ends of the fingers are united together, and

Fig. 7 is a view similar to Fig. 5 with the ends

5 of the fingers in their unswaged state shown in conjunction with the tools that are employed for swaging the adjacent tip ends of the strainer fingers, with the tools positioned just prior to the swaging operation.

Referring now to the drawing in which like numerals designate like parts throughout the several views, the numeral 10 denotes a complete unit plug-type drain or waste fitting such as is used in connection with sinks or lavatory bowls 11 shown in dot-and-dash outline in Fig. 1. The drain fitting comprises a cylindrical tubular shell 12 having a flanged upper end 13 which is adapted to fit into a complementary recess 14 provided in the base of the lavatory bowl 11. The lavatory bowls are usually formed with a depending channel part 15 that provides for an overflow drain passage 16. The outer wall of the tubular shell is provided with a threaded section 17 to which may be threadedly engaged the flanged nut part 18 of an extension tube 19, the flanged nut part adapted to be threaded up against the adjacent underwall portion of the channel part 15 against an interposed washer 20 in securing and sealing the drain fitting 10 rigidly to the lavatory bowl 11.

It is customary to provide the tubular shell 12 of the drain fitting 10 with a circumferential series of overflow drain openings 21 in alignment with the overflow drain passage 16, and in this case there is shown specifically four diametrically opposed overflow drain openings 21 preferably of circular character. To provide for a strainer in the fitting 10, elongated tongues or fingers 22 are sheared out from the stock initially occupied in the overflow openings 21 as indicated by dotted outline in Fig. 2, the proximal ends of these fingers 22 being preferably connected integrally to the tubular shell 12 at the upper ends of their respective openings 21 for reasons as will appear later. It is also to be noted that the overall length of the fingers 22 is such that initially their lower distal ends intercept and extend beyond the normal diameter of the circle as shown by the intercepting cut-out 23 in order to provide sufficient length to the fingers 22 so that when these fingers are subsequently all formed radially inward to their final position, they form strainer fingers 24 that have their ends approaching each other in relatively close relationship, as best shown in Fig. 4, and together forming a cross-like strainer member.

In the past where fingers have been struck out of the walls of the drain fitting and left in the state as shown in Fig. 4, the fingers are no

stronger than the strength that is inherent within themselves and has resulted in some amount of breakage because of the severe strain that is put upon these fingers 24 by the plumbers in assembling the drain fitting 10 to its final attached position to a sink or lavatory bowl or in cleaning out the drainage system. With one or more of the fingers 24 broken out, the strainer feature of the fitting would consequently be considerably impaired.

In order to strengthen these strainer fingers 24 and overcome the above weaknesses, I have accomplished this by axially swaging with a relatively heavy blow the adjacent distal ends of the fingers 24 and by drifting the metal material radially inwardly and laterally as at 25 into a substantially solid interconnected mass except for a relatively small opening 26 in the middle. Specifically the upper surfaces of the fingers 24 are swaged to form a concave socket 27 while the immediate under surface of the fingers 24 are formed into a series of annular rings 28 (see Fig. 5). This particular forming operation is provided to facilitate the drifting factor of the metal material in the finger ends and increase the interlocking feature of the interjoined fingers 24.

It should be understood that, when the strainer fingers 24 of the character here employed, are initially sheared out of the stock of the tubular shell 12, the sheared edges are of a considerably roughened character of numerous small irregular interstices and projections. With this condition of the sheared edges, it was my concept to swage the ends of the fingers 24 with an axial blow sufficient to drift the adjacent edges of the finger material into intimate contact with each other and cause the numerous interstices and projections to interfit into each other and actually knit the metal together in a cross-like juncture as indicated by the wavy junction lines 29 in Fig. 6, which junction lines 29, it should be understood, are somewhat exaggerated.

Fragmentary portions of the tools that are employed to swage the inner ends of the strainer fingers 24 are shown in Fig. 7 and comprise essentially a die 31 having an upper concave surface 32 with cross-like recesses 33 formed therein to accommodate the fingers 24. Concentrically mounted in the die 31 is a plug 34 having annular ridges 35 cut into its upper surface which serve to impress the annular rings 28 into the under surface of the swaged part of the fingers. The inner ends of the fingers 24 in their unswaged state as shown in Fig. 4 are adapted to rest upon the annular ridges 35 of the plug 34 supporting the fitting thereupon prior to the swaging operation. A punch 36 is provided of a size complementary to the inner diameter of the drain fitting, which punch is provided with a domed face 37 somewhat complementary to the arcuate shape of the fingers. The center of the domed face 37 is provided with a spherical projection 38 that serves to swage the concave socket 27 into the upper surfaces of the fingers as previously described. An annular depression 39 separates the spherical projection 38 from the domed surface 37 and is to allow clearance for the drifting of the finger stock coincident with the swaging operation.

It should be noted that the swaging operation at the adjacent ends of the fingers 24 increases the width of the finger tips beyond their original state as clearly indicated by a comparison of Figs. 3 and 6 with Fig. 4 which consequently in-

creases the contacting edge surface engagement of the fingers relative to each other. By joining the ends of the individual fingers 24 together by the inexpensive method of a swaging operation in the manner as indicated, the fingers now become united as one complete unit to serve as a strainer of the drain fitting 10 with all the advantages of one that is made separately for such fittings and subsequently fitted there in place.

Another advantage to be considered in my drain fitting is the fact that the fingers 24 are formed inwardly from the upper edge of the overflow drain openings 21. By so positioning the fingers to serve as a strainer member above the overflow drain openings 21, there is no danger of clogging the overflow drain openings as was the case when the fingers were formed inwardly from the lower edge of the openings as has been the conventional practice.

While I have herein described and upon the drawing shown an illustrative embodiment of a drain fitting, it is to be understood that the invention is not limited thereto but may comprehend other constructions, arrangements without departing from the spirit of the invention and details of construction.

I claim:

1. In a drain fitting comprising a tubular member with a flanged end, said tubular member having oppositely disposed drain openings through the walls, fingers formed inwardly from the edge of said openings toward a common point and on a common plane with their tip ends in abutted relationship adjacent the center axis of said fitting and initially providing an open space between said finger ends, and the abutted ends of said fingers being swaged in spreading the material of the finger ends radially and laterally to the extent of substantially filling up the initial open space and providing for an interconnected jointed union between the finger ends of a reinforced character.

2. A drain fitting as defined by claim 1 wherein the fingers are formed inwardly from the upper edge of said openings.

3. In a drain fitting comprising a tubular member with a flanged end, said tubular member having oppositely disposed openings through its walls, fingers formed inwardly from the upper edge of said openings toward a common point and on a common plane with their tip ends in abutted relationship adjacent the center axis of said fitting, the lengths of said fingers being such as to initially provide for an open space between said finger ends, said fingers collectively forming a cross-like strainer for the fitting located above the openings, and the abutted ends of said fingers being swaged to the extent of spreading the material of the finger ends radially and laterally and have their adjacent edges jammed together to form a substantially solid interconnected center mass, said swaging being effected by tools to produce a concave surface defining the upper portion of said center mass and a series of annular ring surfaces defining its lower portion as a means of producing a greater spread for the swaged material of the finger ends and increase the interconnected portions thereof.

4. In a drain fitting comprising a tubular body with circumferentially arranged drain openings through its wall, fingers sheared from the wall of said body in a manner to produce relatively rough edges, said fingers initially bisecting said openings and bent inwardly and of a length to have their tip ends meet on a common plane

with an open space therebetween, the tip ends of said fingers being axially swaged to radially and laterally spread the ends of the finger stock so that their adjacent rough edges are drifted together into intermingled contact one with the other in substantially filling up the open space and forming a centrally connected cross-joint.

5. The method of constructing a strainer element for a drain fitting which comprises forming a tubular flanged body, shearing elongated fingers out of and at equally spaced position about the wall of said body, bending said fingers inwardly from the wall of said body toward a common point on the body axis, said fingers being initially of a length as to have their tip ends meet at the center with an interposed space therebetween, and gripping and swaging the end portion of said fingers axially of the fitting to the extent wherein the material of said finger ends will be drifted inwardly and laterally toward each other to substantially fill up the interposed space and force the sheared edges of said finger ends into intermingled contact with each other and thus provide an interconnected center joint.

6. The method of constructing a strainer element for a drain fitting which comprises forming a tubular flanged body, shearing oppositely opposed pairs of elongated fingers out of the wall of said body, bending said fingers inwardly from the wall of said body toward a common point on the body axis and in the form of a cross, said fingers being initially of a length as to have their tip ends meet at the center with an interposed space therebetween, and gripping and swaging the end portions of said fingers axially of the fitting to the extent wherein the material of said finger ends will be drifted inwardly and laterally towards each other to substantially fill up the interposed space and force the sheared edges of said finger ends into intermingled contact with each other and thus provide an interconnected center cross-joint.

7. The method of constructing a strainer element for a drain fitting which comprises forming a tubular flanged body, shearing elongated fingers out of and at equally spaced position about the wall of said body, bending said fingers inwardly from the wall of said body toward a common point on the body axis, said fingers being initially of a length as to have their tip ends meet at the center with an interposed space

therebetween, setting the undersurface of said finger ends upon an anvil having a series of annular rings on its working face, and swaging the upper surface of said finger ends downwardly with a ball pointed punch to cause the under surface of the finger ends to be stamped with ring impressions as a means of holding the material of the finger ends and causing a sufficient amount of said material to be drifted inwardly to close up the initial interposed spaces and effect a united butt joint between the finger ends.

8. The method of constructing a strainer element for a drain fitting which comprises forming a tubular flanged body, shearing elongated fingers out of and at equally spaced position about the wall of said body, bending said fingers inwardly from the wall of said body toward a common point on the body axis, said fingers being initially of a length as to have their tip ends meet at the center with an interposed space therebetween, setting the undersurface of said finger ends upon an anvil having an irregular working surface, and swaging the upper surface of said finger ends axially downwardly to cause the material of the finger ends to be stamped with said anvil irregular surface as a means of holding the material of the finger ends and causing a sufficient amount of said material to be drifted inwardly to close up the initial interposed space and effect a united butt joint between the finger ends.
